CLAIM

The ornamental design for a bottle as shown and described.

DESCRIPTION

FIG. 1.1 is a front view of a bottle showing my design;

FIG. 1.2 is a left view thereof;

FIG. 1.3 is a back view thereof; and

FIG. 1.4 is a bottom view of FIG. 1.1

The drawings correspond to a bottle as presented; the evenly spaced broken lines show portions of the bottle that form no part of the claimed design.

1 Claim, 4 Drawing Sheets(56)
